Inventor:
Leopold Frankel
by Leopold Frankel,
Attorney.

UNITED STATES PATENT OFFICE.

LEONHARD TREUHEIT, OF ELBERFELD, GERMANY.

TESTING DEVICE.

Application filed June 23, 1924. Serial No. 721,782.

To all whom it may concern:

Be it known that I, LEONHARD TREUHEIT, a citizen of Germany, residing at Elberfeld, Germany, have invented certain new and useful Improvements in Testing Devices, of which the following is a specification.

My invention relates to a device for ascertaining the compression strength of granular substances and more especially the consolidation of sand, composition and loam moulds.

As is well known to those skilled in the art, the consolidation of moulds and cores is an important factor in foundry practice as it influences to a great extent the quality of castings obtained. If the material is too strongly compressed, it lacks porosity and the gases cannot escape. If it is too loose, the moulds are expanded and the weight of castings is unduly increased.

By examining the consolidation of the moulds and rejecting such as are too compact or too loose, defective castings can be avoided.

It is an object of my invention to provide a simple and reliable testing device for the purpose specified.

In the drawings affixed to this specification and forming part thereof, two devices embodying my invention are illustrated diagrammatically by way of example. In the drawings—

Fig. 1 is a longitudinal section of a vertical tester and

Fig. 2 is an elevation partly in section of a horizontal tester.

The vertical tester shown in Fig. 1 comprises a hollow cylinder *a* having the form of a tubular handle, a hollow slide or piston *b* reciprocating therein, a cap *g* with a central opening at the bottom of the cylinder and a measuring dial and pointer *e* connected with the piston *b* by a pin *d*. A hardened steel ball *c* is seated in the lower end of the piston *b*, and the piston is weighted by shot or the like *f*.

The horizontal tester, Fig. 2, is of similar construction but has an angular cylinder. The steel ball is secured in a piston *h* which is guided in the horizontal portion *i* and connected with the hollow piston *b* in the vertical portion of the cylinder by a bell crank lever *m* pivoted at *l* and links *m'*, *m''*.

Means are further provided for drawing the ball *d* into the cylinder *i* and locking

the piston when the implement is not in use. To this end a sleeve *n* comprising a cam face *o* is placed on the upper end of the cylinder which is slotted at *p* and a pin *q* projecting from the slot and secured in the piston *b* rests on the cam surface *o*.

When the sleeve *n* is turned to the left in Fig. 2, the pin *q* is raised, carrying the piston *b* along and drawing the ball *c* into the cylinder *i* through the medium of the bell crank lever *m*.

The operation of the novel device is as follows:—

The bottom of the handle is placed on the mould, core, etc. to be tested and the piston *b* is released by turning the sleeve *n*. The ball *c* will then make an impression in the mould whose depth is determined by the weight of the piston and the consolidation of the mould and indicated by the dial *e*.

The compression strength may be calculated by dividing the load on the ball by the surface of the impression whose depth is indicated by the dial *e*. Preferably a table is secured on the outside of the cylinder *a* on which the compression strength corresponding to the depth of impression may be read directly.

The tensile strength of sand, etc., is a function of its compression strength so that the tensile strength may be calculated from the dial indications and tabulated as described.

Moulds, cores etc. can thus be tested without any loss of time, a vertical or horizontal testing device being used in accordance with the position of the surfaces to be tested.

I wish it to be understood that I do not desire to be limited to the exact details of construction shown and described, for obvious modifications will occur to a person skilled in the art.

I claim:—

1. Testing device for ascertaining the compression strength of granular substances comprising a tubular handle, a slide adapted to reciprocate in said tubular handle and provided at one end with a contact surface for engaging a test piece and means on the other end of said handle for indicating the travel of said slide and an operative connection between said slide and said indicating means.

2. Testing device for ascertaining the compression strength of granular substances

2
comprising a cylindrical handle, a piston-like slide adapted to reciprocate in said handle, a ball secured to one end of said slide and means on said handle for indicating the stroke of said slide.

3. Testing device for ascertaining the compression strength of granular substances comprising a cylindrical handle, a hollow piston-like slide adapted to reciprocate in said handle, weighting means in said handle, a ball secured to one end of said slide and means on the other end of said handle for indicating the stroke of said slide.

4. Testing device for ascertaining the compression strength of granular substances comprising an angular tubular handle, two slides operatively connected with each other and arranged for reciprocation in different parts of said tubular handle, a ball secured to one of said slides and means on said handle for indicating the travel of said slides.

5. Testing device for ascertaining the

compression strength of granular substances comprising a cylindrical shell, a piston-like slide adapted to reciprocate in said handle, a ball secured to one end of said slide, means on said handle for indicating the stroke of said slide, a sleeve rotatably carried on said handle, a cam face on said sleeve and a pin secured to said slide and adapted to cooperate with said cam face.

6. Testing device for ascertaining the compression strength of granular substances comprising an angular tubular handle, two slides operatively connected with each other and arranged for reciprocation in different parts of said handle, a ball secured to one of said slides, means on said handle for indicating the travel of said slides and means for locking one of said pistons in said handle.

In testimony whereof I affix my signature.

LEONHARD TREUHIEIT.
